UNITED STATES PATENT OFFICE

BJARNE FRIDHOLM, OF BROOKLYN, NEW YORK

CLOTHESLINE SUPPORT

Application filed March 15, 1932. Serial No. 598,923.

This invention relates to new and useful improvements in aerial clothes lines, and has for its main object to eliminate the danger to a person, or housewife, incidentally to leaning out of a window, when hanging out or removing clothes for drying.

As this device comprises comparatively few parts, and as the construction is rather simple, the cost of manufacturing the same should 10 be proportionately low.

With the above and other objects in view, this invention consists of the novel features of construction, combination and arrangement of parts, hereinafter fully described, 15 claimed and illustrated in the accompanying drawing forming part of this specification, and in which similar characters of reference indicate corresponding parts in all views, and in which:

20 Figure 1 is a side elevation of my device in full extended form, that is with the major arm projecting from the open window into the room.

Figure 2 is a top plan view of my device as 25 shown in Figure 1. Figure 3 is a detail view showing the relative arrangement of a pulley system; while Figure 4 is another detail view, and Figure 5 shows my device in actual operation, that is with the clothes line connected to a pole.

Referring more particularly to the drawing, 11 is a jamb of the window-frame to which is attached at the outer side the carrier 12 of the aerial clothes-line-fastener of 30 my invention, as seen in Figure 2; this carrier is preferably of a rectangular form, so that its free end with the clothes-line or rope-fastener extends from the lateral window-jamb to the space in front of the window-opening, to facilitate the operation of the device. To the carrier 12 are riveted or screwed the middle parts of two short bars 13, 14 of rectangular cross section, the free ends of which bars are twisted at a 90 degree angle 35 and are rounded off, with holes in their centers, so that they may serve as hinges for the other parts carried by them. The two hinges 15, 16 which face the open space outside the house, carry clamps 17, 18, riveted to two arms extending from the middle part of the

holder 19 of the two outdoor-pulleys 20, 21, so that these rope-pulleys are arranged vertically the one above the other. The ends of the pulley-holder 19 project somewhat beyond the circumferences of their respective 45 pulleys 20, 21, so as to protect the clothes-line or rope from jumping its track on the pulleys.

At the other free ends of the short bars 13, 14, which face the window-opening or towards the inside of the house, are provided 50 two more hinges 22, 23, carrying clamps 24, 25, which with their middle parts hold a pair of guide-pulleys 26, 27 surrounded by rope-fencing tongues 28, 29, as seen best in the Figure 3. To the other ends of the clamps 24, 25 at 30 and 31, respectively is hinged the longer bar 32, comprising two members, 55 which are braced together at different places of their length, so as to form a well stiffened rigid swingable arm. The bracing yoke 34 at the swinging end of this arm surrounds the opposite pulley 35 of the clothes-line. In consequence of the three pairs of hinges the whole device may be stretched in a straight 60 line as shown in the Figures 2 and 5 (in full lines), in which position the swingable arm 32, reaches through the window opening partly into the house, or this arm 32, may be swung round the two pairs of hinges 22, 23 and 30, 31 out of the room or house into the position 65 indicated by the pointed lines in Figure 2, so that this arm extends parallel to the main part of the clothes-line or rope.

From the foregoing description of the construction the manipulation of this new and improved device may readily be understood to be as follows:

An endless clothes-line or rope 36 encircles 70 a second pulley 37 arranged in the yard at a pole 38 opposite to the place of the present device, as shown in Figure 5. The upper portion of the endless rope 36 is conducted from the outer pulley 37 into the groove of the pulley 20 and from there through the groove of the pulley 26 to the opposite-pulley 75 35 of the rope-fastening device at the house; after encircling this opposite pulley 35 the lower portion of the rope goes back over the grooves of the two lower guide-pulleys 27 and 21 to the pulley 37 at the outer pole 38. 80

If the house-wife or other user of the device wishes to hang up clothes or other washed goods for drying then she takes the lower portion of the rope out of the grooves of the 5 lower guide-pulleys 27 and 21, so that this lower portion hangs freely between the two pulleys 35 and 37, then she fastens the clothes on the lower portion and shifts them step by step out into the open air. Whereas with 10 the older well-known arrangement of the hang-out rope the person had to lean far out of the window, which made the work of fastening the clothes on the rope a very tiresome and extremely dangerous task. As will be 15 noted a person who uses my invention may fasten the clothes to the rope while standing comfortably within the room, as the longer arm 32, of this new and improved rope-supporter reaches through the window opening 20 well into the room. When all the clothes are hung on the rope and shifted out into the open air, then the user puts the lower portion of rope again between the fencing tongues and into the grooves of the guide-pulleys 27 25 and 21. When this is done, the longer arm 32, of the device may be swung round the two pairs of hinges 22, 23 and 30, 31 into the position shown in Figure 2 by dotted lines, in which position this longer arm extends to 30 wards the outer open space. Thus it is removed out of the window opening and the window sash may be closed again, while the clothes or wash is hanging outside for drying. Even with this last-described position 35 of the long arm 32, doubling back towards the outside, the rope 36 remains unchanged in tensioned position, as it is held within the grooves of the guiding-pulleys 26, 27, which are centrally arranged upon the bracket. 40 The new and improved rope-supporter according to my invention is built symmetrical- 45 ly to both sides of its longitudinal axis and as it is seen in Figure 1, it may be fastened either to the right-side jamb or to the left-side jamb of a window frame; and further the holder 19 of the two outdoor guide-pulleys 20, 21 may be swung slightly round the hinges 15, 16 if the outside fastening pole 38 is not situated straight in front of the window- 50 opening but somewhat more to the side. Two eyelets 39, 40, provided at the beforesaid holder 19 and at the longer arm 32, respectively further allow an additional bracing of the rope-supporting device by inserting into 55 these eyelets suitable hooks which may be fastened at other points of the window-frame.

It is obvious that changes may be made in the form, construction and arrangement of the several parts, as shown, within the scope 60 of the appended claims, without departing from the spirit of the invention, and I do not therefore wish to limit myself to the construction and arrangement shown and described herein.

65 What I claim as new, and desire to secure

by Letters Patent of the United States, is:

1. A support for aerial clothes-lines or ropes, comprising in combination, a carrier to be fastened outside at a window-frame or wall and reaching to the outside space in front of the window-opening, a longer arm hingedly connected to parts at the end of the said carrier and adapted to be swung through the window-opening partly into the interior of a room, or to be swung back towards the open space outside of the window-opening, a reversal-pulley for the clothes-line or rope arranged at the free swinging end of the arm, a shorter arm extending from the aforesaid end of the carrier in the direction opposite to the parts carrying the longer arm, a pair of guide-pulleys for the clothes-line or rope at the end of the said short arm, and a pair of intermediary guide-pulleys for the clothes-line or rope close to the hinges carrying the said swingable longer arm.

2. A support for aerial clothes-lines or ropes, comprising in combination, a carrier fastened outside of a window and reaching to the open space in front of the window-opening, pairs of hinges arranged at two opposite ends of the carrier in a direction through the window, a short arm held in the hinges arranged at the carrier-end nearer to the open space in front of the window, a pair of guide-pulleys for the clothes-line or rope at the free end of the said shorter arm, a longer arm held in double hinges arranged at the carrier-end nearer to the window, a reversal-pulley for the clothes-line or rope at the free end of the longer arm, another pair of guide-pulleys for the clothes-line or rope arranged close to the said double hinges in such a manner, as to guide and hold the clothes-line or rope tensioned for all the different adjustments of the swingable longer arm, the arrangement of all the guide-pulleys being such, as to allow a temporary disengagement of the clothes-carrying line from the guide-pulleys carrying it during the hanging-out or removal of the clothes.

3. A support for aerial clothes-line or ropes, comprising in combination, a carrier fastened outside of a window and reaching to the open space in front of the window-opening, pairs of hinges arranged at two opposite ends of the carrier in a line of direction going through the window, a short arm held in the hinges at the carrier-end which is situated nearer to the outside in front of the window, a pair of guide-pulleys for the clothes-line or rope at the free end of the said short arm, a longer arm held in double hinges situated at the carrier end nearer to the window, a reversal-pulley for the clothes-line or rope at the free swingable end of the longer arm, another pair of guide pulleys for the clothes-line or rope arranged close to the said double hinges in such a manner as to guide the clothes-line or rope and to hold it tensioned 115 120 125 130

in all the different adjustments given to the swingable longer arm, and rope-fencing tongues surrounding each one of the said guide-pulleys in such a manner, as to allow a temporary removal of the rope from the grooves of the pulleys carrying the said clothes-line.

4. A support for aerial clothes-lines or ropes, as claimed in claim 1, with such arrangement of the parts as to be symmetrical with reference to the longitudinal axis of the whole device, so as to permit of its fastening at either side of a window opening.

Signed at New York City, in the county of New York, and State of New York, this 16th day of February, A. D. 1932.
